UNITED STATES PATENT OFFICE.

ROBERT E. L. JANNEY, OF CHICAGO, ILLINOIS; GARDNER L. BOOTHE EXECUTOR OF
SAID ROBERT E. L. JANNEY, DECEASED.

CARBURETOR.

Application filed May 7, 1920. Serial No. 379,537.

To all whom it may concern:

Be it known that I, ROBERT E. L. JANNEY, a citizen of the United States, residing at Chicago, county of Cook, State of Illinois, have invented certain new and useful Improvements in Carburetors, of which the following is a specification.

My invention relates to carburetors, more especially designed for use in connection with internal combustion engines, and has for its objects to provide certain improvements in the construction disclosed in application for Letters Patent, filed by me November 21, 1914, Serial No. 873,301, and in Letters Patent No. 1,342,445, granted to me June 8, 1920, of which this application is a continuation in part.

One object of my invention is to maintain practically a constant speed of air at all times at the point of its admission into the mixing chamber, the air being admitted in thin annular sheets, one surrounding another, thus exposing a large surface area of air to the action of the fuel. A further object is to introduce the component parts of the mixture into the mixing chamber by a series of Venturi tubes, one emptying into the other, said tubes providing intervening mixing spaces, which tend to draw the fuel from the center to the outer layers of air. Other objects of my invention are to control the component parts of the fuel before their admission to the mixing chamber, by positively operated valves; to eliminate all pockets and obstructions to the free flow of the mixture from the mixing chamber; to expose the fuel to a preliminary breaking up process before its admission to the mixing chamber; to cause the surplus fuel to drain directly into the path of the incoming air; to eliminate all butterfly and spring-controlled admission valves; to provide a predetermined amount of air to the fuel supply tube to assist in breaking up the fuel as it passes from said tube to its outlets; to provide for heating the fuel at a point between the float chamber and the jet, and to regulate the flow of fuel by mechanical variations between the valves.

These objects I accomplish in the manner and by the means hereinafter described and claimed, reference being had to the accompanying drawings, in which:—

Figure 1 is a central vertical sectional view of a carburetor embodying my im-

proved construction, the parts being shown in position to maintain a low speed in the internal combustion engine.

Figure 2 is a transverse sectional view taken on the line II—II of Figure 3.

Figure 3 is a view similar to Figure 1, taken at a right angle thereto, part of the internal construction being shown in full lines.

Figure 4 is a detail vertical sectional view of a slightly modified construction of the fuel supply control mechanism.

Similar numerals of reference denote corresponding parts in the several views.

In the said drawings, referring more particularly to Figures 1, 2 and 3, the reference numeral 1 denotes the mixing chamber of the carburetor, the same being shown slightly tapered at its upper portion and adapted to be connected with the usual manifold of an internal combustion engine. Said chamber 1 is detachably attached at its lower end to a casing 2; which has attached thereto at one side the usual float chamber 3, the latter, as shown in Figure 1, containing a conventional float 4. The bottom of the chamber 3 is provided with a fuel discharge aperture 5, leading into an enlargement 6 of a fuel passage 7, said enlargement containing a conventional electric coil 7' for subjecting the fuel to a heating action, said coil being controlled by the usual rheostat, in a manner readily understood. The passage 7 communicates with an annular chamber 8, formed in the casing 2, and also connecting said chamber 8 directly with the chamber 3 is a supplemental passage 9, for a purpose hereinafter to be described. The chamber 8 is formed between the wall of the casing 2 and an interior tube 10, permanently located therein, said tube being slightly tapered at its upper end at 11 and fitted within an exterior tubular casing 12 spaced sufficiently from said tube 10 to provide an annular fuel passage communicating with the chamber 8. Formed integral with an annular cap 13 attached to the top of the tubular casing 12 is an inverted cone 14 provided annularly with a series of minute perforations 15 providing passages therethrough for the mixed air and fuel, as hereinafter described. Disposed within the tube 10 and longitudinally adjustable therein is a stem 16 tapered at its upper end to form a needle valve 17 and enlarged at its

lower portion to fit within the tube 8 and also within the casing 2, as shown. Said stem is adapted removably to receive at its lower end a plug 18 having a vertical passage therethrough communicating with an interior passage 19 in said stem extending part way up the same and terminated in lateral apertures 20 communicating with an annular space between said stem and the sleeve 10, as shown.

In order to guide the spaced end of the stem 16 in the sleeve 10, I provide a series of ribs 21 on said stem contacting with the interior of said sleeve 10, but permitting the free passage of air therearound. As shown, the upper needle valve end 17 of the stem 16 fits in a correspondingly shaped aperture 22 in the tubular casing 12, which just beyond the upper end of said needle valve expands into a chamber 23, the same being approximately in the form of a Venturi tube, and communicating with the apertures 15, said chamber effecting a preliminary breaking up of the fuel before it reaches the main air supply. The lower end of the stem 16 is in screw-threaded engagement with a plate 24, a suitable spring arm 25 being fixed to said plate and engaging a serrated flange 26 on said stem 16 whereby said stem may be adjusted vertically with respect to said plate 24, and retained in any adjusted position. The plate 24 extends to one side, and has screwed in an aperture therein an adjusting screw 27 recessed at its upper end to receive a coiled spring 28 with which loosely engages a link 29. Said screw 27 is internally apertured at 30 to receive a bolt 31 in screw-threaded engagement with a bracket 32 supported from the casing 2, a coiled spring 33 being interposed between said screw 27 and bracket 32, and a spring arm 34, similar to the spring arm 25, is carried by said bracket 32 and adapted to engage a serrated flange 35 on said screw bolt 31, all for a purpose hereinafter to be described. Similarly a spring 34' on the plate 24 engages a serrated flange 35' on the screw 27 and for a similar purpose. The upper end of the link 29 is pivoted to a bell crank lever 36, in turn pivoted at 37 in the casing 2, the upper end of said bell crank being adapted to be operated in any suitable manner, as from the dash of an automobile for controlling my improved mechanism, as hereinafter described. The inner end of said bell crank lever 36 is bifurcated and adapted to engage trunnions 38 formed on a sleeve 29, which has fixed to its upper end a sleeve valve 40 surrounding the tubular casing 12, and vertically movable thereon. Said sleeve valve fits within a central conical aperture formed in a casting 41, which is permanently held between the mixing chamber 1 and the casing 2 by means of a ring 42 clamped therebetween, a pin or pins 43

passing through said ring and into said casting for retaining the two parts together when the several elements are assembled. As shown in Figure 1, the interior of the casting 41 is conical at 44 and its angle corresponds exactly with the exterior surface of the valve 40, as shown. The sleeve 39 is provided with an exterior shoulder upon which rests a coiled spring 45, the upper end of which engages a corresponding interior shoulder in a sleeve 46 surrounding the sleeve 39, said sleeve 46 having fixed thereto arms 47, which are in turn fixed to an annular conical valve 48, disposed in the mixing chamber 1 and having its exterior surface formed at the same angle as the interior surface of said chamber 1, as shown. Disposed in screw-threaded engagement with an enlargement 49 on one of the arms 47 is a threaded rod 50 passing freely through the lower end of the casing 2 and provided with an operating thumb piece 53. The upper end of this rod 50 is adapted to contact with the casting 41, being disposed in a recess 54 formed therein. The rotary movement of said rod 50 is controlled by a serrated flange 55 with which engages a spring 56 carried by the arm 47. Mounted in screw-threaded engagement with the sleeve 46 near its lower end is a stop ring 57, the same being serrated on its exterior surface to receive a spring 58 for preventing accidental rotation, but adapted to be adjusted vertically on said sleeve 46, for a purpose hereinafter to be described. Mounted in the casing 2 is a threaded stop screw 59 adapted to contact with a projection 60 on the bell crank lever 36 adjustably to limit the movement of the lever to the right. Mounted on a bracket 61 carried by an extension from the casing 2 is a bell crank lever 61', the same having pivoted thereto at its inner end a pin 62 adapted to contact with the plate 24, a suitable operating cord 63 being attached to the opposite end of said bell crank lever 61', so that the pull on said cord will depress the plate 24 and consequently the needle valve 17.

The operation of my improved device will be understood as follows: With the parts in the position shown in Figures 1 and 3, it will be observed that the valves 40 and 48 are slightly open, their position being governed by the adjustment of the rod 50 for the valve 48 and the screw 59 for the valve 40, it being understood that the spring 45 normally presses the valve 48 towards its uppermost position, which movement is limited by the adjusted engagement of the rod 50 with the casting 41. In a similar manner, the upward movement of the valve 40 is governed positively by the bell crank lever 36 whose movement towards the closed position of said valve is adjustably limited by the set screw 59. With said valves in this

position, the needle valve 17 being properly adjusted to afford a slight annular opening at the passage 22, and there being a space between said valve and the sleeve 10, there will be a constant supply of air upward through the plug 18, and around the stem 16, while the constant supply of fuel will be afforded through the passages 5 and 7, the fuel being heated by the electric coil 7', and passing into the chamber 8 and thence upwardly around the sleeve 10 to the needle valve. There being no butterfly valve in the mixing chamber 1, the full suction of the engine will be exerted directly upon the apertures 15 in the cone 14, thus causing a flow of mixed fuel and air into the small mixing chamber 23, the air being sufficient in quantity only to serve to effect a preliminary breaking up of the fuel. It will be understood that as the plug 18 is removable, the same may be replaced by a similar plug with a larger or smaller aperture therein, if desired, to vary the quantity of air admitted at this point to the carburetor. The apertures 15 being equidistant from the aperture 22, the mixed fuel and air thus preliminarily broken up, passes equally through all of said apertures 15 into the venturi formed in the casting 41, the chamber 23 and the cone 14 being of such shape as to guide the mixture direct to said apertures 15, thus avoiding the formation of pockets. The mixture there is met by the incoming additional air passing around the slightly open sleeve valve 40, this mixture discharging into the mixing chamber 1 and in its passage therethrough, being met by additional air passing around the slightly open exterior sleeve valve 48. Assuming this to be a supply sufficient to permit the internal combustion engine to operate, when it is desired to increase speed, the upper end of the bell crank lever 36 is moved to the left, which causes the link 29 to contact with the spring 28, and as said spring is of equal tension with the lower spring 33, a further movement will cause the plate 24 to be forced downward, carrying with it the stem 16 and its needle valve 17, thus increasing the opening at 22, whereby the supply of fuel therethrough will be increased proportionately, while at the same time the downward movement of the inner end of the bell crank lever 36, through the trunnions 38 will force down the sleeve 39, carrying with it the inner valve 40, thus increasing the annular air opening at that point and affording a proportionately additional air supply to meet the mixture discharging through the apertures 15. A further movement of the upper end of the bell crank lever 36 to the left will depress the needle valve 17 and the sleeve valve 40 still further, thus further increasing the area of both openings, and if this movement is car-

ried far enough the trunnions 38 will contact with the ring 57 on the sleeve 46, and further movement thereof will depress said sleeve, which, through the arms 47, will carry with it the exterior annular valve 48, thus further opening said valve. The plate 24 may be depressed in this manner until the top of the adjusting screw bolt 31 contacts with the top of the recess 30 in adjusting screw 27, which thus limits the maximum downward movement of the plate 24. It will thus be seen that the screw bolt 31 controls the maximum opening of the needle valve, and by adjusting the screw 27 vertically in the plate 24, the relation of the spring 28 to the link 29 may be varied so as to vary the time of the initial contact thus effecting an intermediate adjustment. Similarly the low speed adjustment of the device is controlled by the vertical disposition of the stem 16 and needle valve 17, which may be varied at will through its screw-threaded engagement with the plate 24. Similarly by varying the relative strength of the springs 28 and 33, a variation in the time of the opening in the needle valve will be effected. Thus, by making the spring 33 slightly stronger than the spring 28, the opening of the valve will be delayed, whereas by reversing the relative strengths of these springs, the opening of said valve will be accelerated. Under this latter condition it will also be observed that when the needle valve 17 is opened to its limit, with the elements 27 and 31 contacting, the sleeve valves 40 and 48 may be opened still further to supply additional air, by further movement of the bell crank 36, the yield of the spring 28 permitting this additional movement.

When the level in the float chamber 3 falls below the passage 9, the suction of the engine will be satisfied by air passing through said passage 9, thus cutting off the fuel supply, stopping the engine, and cutting off the electric current.

By adjusting the stem 50 vertically, the upward limit of the movement of the outer valve 48 may be determined as accurately as may be desired, while by an adjustment of the ring 57 on the sleeve 46 the time of contact therewith of the trunnions may be determined with extreme accuracy. So also by adjusting the set screw 59 the outward limit of movement of the inner end of the bell crank lever 36, and with it the upward or closing movement of the inner annular valve 40, may be determined with accuracy.

In order to provide for priming the carburetor, I employ the bell crank 61 which upon being actuated will, through the pin 62, depress the plate 24, thus increasing the fuel supply through the aperture 22 as may be desired.

In Figure 4 I have shown a modified con-

struction of fuel supply, wherein the central stem 64, which corresponds with the stem 16 of the construction shown in Figures 1 to 3, has a central air passage 65 therethrough and is surrounded by a fuel supply passage 66, the flow of fuel being controlled by the vertical movement of said stem 64, operated as is the stem 16 of Figure 1, through the restricted or venturi opening 67 into the expanding chamber 68, there being a single restricted central discharge 69 therefrom, which discharge is into the venturi formed in the casting 41 of the construction shown in Figures 1, 2 and 3.

15 However, the cone 14 may be substituted for the discharge 69 if desired.

By forming the wall of the mixing chamber 1 perfectly straight and by disposing the outer valve 48 as shown, a constant supply of air is admitted within the mixing chamber in a thin jet-like sheet which sweeps the straight inner wall of the mixing chamber, thus exposing a larger surface area of air traveling at high velocity to act on the fuel. Furthermore, any fuel which may lodge on the wall of the mixing chamber 1 will drain directly into the path of this sheet of air and then will be caught up and atomized. There being no curves whatever in the wall of the chamber 1 any danger of pockets for the collection of fuel is avoided in a most thorough manner. It will be understood that the normal opening of the valve 48, when in its uppermost position, is extremely slight, though it is desirable that there be a very minute passage of air therethrough at all times. The same effect is obtained in the passage through the casting 41, due to the slight normal opening of the valve 40, as any down flow of fuel along the inclined walls of this passage will be caught up by the film of air passing upwardly past said valve. Furthermore, any fuel depositing or condensing upon the cone 14 will flow down past the openings 15 and be caught up by the air current passing said opening and carried upward. The ring 13 is so formed, with respect to the core 14, that its upper edge projects slightly outside of the widest diameter of said core so that the passage of air past the same coming through the valve 40 will cause a slight vacuum at this point thereby aiding the flow of the mixture through the apertures 15, in a manner readily understood. This has the effect of throwing the mixture away from the wall beyond the openings 15, and projecting the fuel directly and symmetrically into the cone of incoming air at an angle thereto.

60 The vacuum produced in the intake manifold of an internal combustion engine generally is regulated by a controlling valve placed in the carburetor between said manifold and the mixing chamber. Under these conditions the full effect of the vacuum is felt in the intake manifold only and never in the carburetor. That is to say, it extends to the controlling valve only, the fuel mixing chamber being open to atmospheric pressure. When said controlling valve is partly open 70 the speed of the mixture may be high at this point but sluggish in the mixing chamber. The passageways leading to the mixing chamber are of sufficient area to accommodate the maximum amount of air required, 75 so that the speed of air through these passageways varies in proportion to the opening of the controlling valve. If the speed is comparatively slow the incoming air on reaching the mixing chamber will form eddies or pockets, and these will be exaggerated because the stream of the mixture is diverted to one side by said controlling valve. Likewise, the control of the fuel supply is made more difficult because of the 80 varying degree of the vacuum, as well as the speed of the incoming air. In my device, I place the controlling valve or valves in advance of the mixing chamber and of the fuel supply, so that the full effect of the vacuum 85 may extend to the mixing chamber and fuel supply. By placing these valves imminently in advance of the mixing chamber the air enters said mixing chamber at its highest speed. Furthermore, these valves are 90 so arranged as to have a nozzle-like effect, and their opening sharply enlarges the area of the nozzle without changing its character. The manifold vacuum always being maintained in the mixing chamber, the mixture 95 flows freely in the direction of this vacuum and air pockets are avoided. However, better to accomplish this result, the outer funnel-like walls of the mixing chamber must be symmetrical and must not depart 100 from a straight line between the point where the air leaves the outer valve and that where it leaves the mixing chamber.

105 It is very important to maintain an approximately constant speed of air and to 110 take advantage of that speed, both for its aspirating and atomizing effect. By placing the inner valve 40 immediately in advance of the fuel jets 15 the air passes the jets at high velocity, thus greatly increasing 115 the aspirating effect. The outer valve 48 is placed immediately in advance of the mixing chamber, and is of such shape as to admit the air equally to all sides of said chamber, greatly increasing the atomizing effect. 120

125 In the use of the heavier fuels, it is sometimes desirable to preheat them. For this reason, the heating coil 7 is placed in the position shown, that is to say, between the float chamber and the jet. Such preheating in bulk causes the separation of the lighter portions of fuel, and is not effective unless the preheating is arranged to take place immediately before the fuel enters the nozzle and directly beneath the same. In the ar- 130

angement shown, I obtain a circulation of fuel so that the hottest part of it will be contained in the chamber 8 leading to the jet and directly below the same. The fuel in the float chamber should not be heated at all, that is, practically not at all.

The vertical disposition of the interior passage 19 in the needle valve stem 16 provides a very efficient means for keeping said passageway open at all times, it being evident that part of the fuel which may collect in the chamber 23 will when the engine is stopped pass down around the needle valve and through the lateral apertures 20 into the interior passage 19, and will discharge through the aperture in the plug 18, thus serving at all times to keep the said passageway free from any collection of dust, dirt, or other foreign matter. This is important, as the opening through the plug 18 is quite restricted, the supply of air at this point being sufficient only to serve for a preliminary breaking up of the fuel in the chamber 23.

Having thus described my invention, what I claim as new and desire to secure by Letters Patent, is:

1. In a carburetor, a mixing chamber, a fuel supply means, inner and outer air supply means, inner and outer valves controlling said air supply means and placed in advance of the mixing chamber, and mechanical means for operating said valves, said means operating to open said outer valve after said inner valve is opened, and to close said outer valve before said inner valve is closed.

2. In a carburetor, a primary mixing chamber, a fuel supply means therefor, an air supply means therefor, a sleeve valve surrounding said chamber, a main mixing chamber receiving the mixture from said primary chamber and an additional sleeve valve controlling a supplemental annular air supply passage admitting air to said main mixing chamber.

3. In a carburetor, a fuel supply means, an air supply means, a sleeve valve surrounding the discharge outlets of said fuel and air supply means, a chamber receiving air and fuel from said supply means, an additional sleeve valve controlling a supplemental annular air supply means surrounding said chamber, and a common means for successively operating said sleeve valves.

4. In a carburetor, a fuel supply means, an air admitting means, a mixing chamber having a discharge outlet for mixed fuel and air, an air supply means surrounding said discharge outlet, a secondary mixing chamber with which said air supply means communicates, a supplemental air supply means surrounding said secondary mixing chamber, sleeve valves controlling the said air supply means, a common means for oper-

ating said sleeve valves, and adjustable means whereby the successive operation thereof may be varied.

5. In a carburetor, a fuel supply means, inner and outer annular air supply means, valves controlling said air supply means, and a mixing chamber receiving fuel from said fuel supply means having its wall tapered in a straight line to its discharge outlet, the outer air supply discharging annularly into said chamber along its wall.

6. In a carburetor, a primary mixing chamber, a fuel supply means therefor, and an inverted cone forming the top of said chamber, the connection between said chamber and cone being provided with an annular series of small apertures for discharging outwardly and angularly therefrom.

7. In a carburetor, a primary mixing chamber, a fuel supply means therefor, an inverted cone forming the top of said chamber, the connection between said chamber and cone being provided with an annular series of small apertures for discharging outwardly and angularly therefrom, an air supply surrounding said chamber, and a sleeve valve for controlling said air supply.

8. In a carburetor, a primary mixing chamber, a fuel supply means therefor, and an inverted cone forming the top of said chamber, the connection between said chamber and cone being provided with an annular series of small apertures for discharging outwardly and angularly therefrom, the outer wall of said chamber adjacent said apertures lying outside the latter and being inclined downwardly and inwardly towards said apertures.

9. In a carburetor, a primary mixing chamber, a fuel supply means therefor, an inverted cone forming the top of said chamber, the connection between said chamber and cone being provided with an annular series of small apertures for discharging outwardly and angularly therefrom, a casting surrounding said chamber and provided with a central tapered straight walled orifice spaced from the outer wall of said chamber into which the fuel discharges, and a sleeve valve in said orifice in advance of said discharge for controllably admitting air in a thin annular sheet.

10. In a carburetor, a fuel supply means, a primary air supply means therefor, inner and outer air supply means, valves controlling said inner and outer air supply means, a needle valve for controlling said fuel supply, and a common control for said needle and air valves.

11. In a carburetor, a fuel supply means, a primary air supply means of fixed area therefor, inner and outer secondary air supply means, valves controlling said inner and outer supply means, a needle valve for controlling said fuel supply, and a common con-

6
trol for said needle and air valves, the same operating to open and close said needle and inner air valves simultaneously and to open said outer valve after said inner valve is opened, and to close said outer valve before said inner valve is closed.

12. In a carburetor, a fuel supply means, inner and outer air supply means, valves controlling said inner and outer air supplies, 10 and a spring interposed between said valves and exerting its tension on said outer valve towards its closed position and on said inner valve towards its open position.

13. In a carburetor, a fuel supply means, 15 inner and outer air supply means, valves controlling said inner and outer air supplies, a spring interposed between said valves and exerting its tension on said outer valve towards its closed position and on said inner 20 valve towards its open position, and adjustable means for controlling the closing movement of said outer valve.

14. In a carburetor, a fuel supply means, inner and outer air supply means, valves 25 controlling said inner and outer air supplies, a spring interposed between said valves and exerting its tension on said outer valve to-

wards its closed position and on said inner valve towards its open position, and separate means for adjustably controlling the closing 30 movement of said valves.

15. In a carburetor, a fuel supply means, inner and outer air supply means, valves controlling said air supplies, a spring interposed between said valves and exerting its 35 tension on said outer valve towards its closed position and on said inner valve towards its open position, and mechanical means for operating said valves, said means operating to open said outer valve after said inner 40 valve is opened and to close said outer valve before said inner valve is closed.

16. In a carburetor, a fuel supply means, a needle valve for controlling the same, means for adjusting said needle valve, an 45 air supply passage in said needle valve, and a removable apertured plug at the lower end of said air passage, the aperture therein determining the air admission through said 50 needle valve.

In testimony whereof I hereunto affix my signature.

ROBERT E. L. JANNEY.
